UNITED STATES PATENT OFFICE.

WILLIAM W. BENNETT, OF MESQUITE, TEXAS.

TELEPHONE SYSTEM.

SPECIFICATION forming part of Letters Patent No. 628,068, dated July 4, 1899.

Application filed December 1, 1897. Serial No. 660,339. (No model.)

To all whom it may concern:

Be it known that I, WILLIAM W. BENNETT, a citizen of the United States, residing at Mesquite, in the county of Dallas and State of Texas, have invented a new and useful Telephone System, of which the following is a specification.

This invention relates to telephone systems; and it has for its object to provide a novel arrangement of circuits in connection with a pair of telephone-receivers at each subscriber's station, whereby the subscriber can cut out the section of the main line at either side of his station, so that the conversation being carried on between two subscribers cannot be heard by the other subscribers on the same line.

The improved system contemplated by the present invention is only intended for use in connection with telephone systems wherein a plurality of instruments are in the same main-line circuit and aims to overcome the objection of all subscribers on the same main line being able to hear conversation carried on between any two subscribers.

With these and other objects in view, which will readily appear as the nature of the invention is better understood, the same consists in the novel construction, combination, and arrangement of parts, hereinafter more fully described, illustrated, and claimed.

In the drawings, Figure 1 is a perspective view of a subscriber's telephone apparatus provided with a pair of receivers as contemplated by the present invention. Fig. 2 is an interior view of the bell-box, showing the side thereof fitted with the two sets of switch-springs. Fig. 3 is a detail sectional view on the line 3 3 of Fig. 2. Fig. 4 is a detail in perspective of the receiver switch lever or hook. Fig. 5 is a diagram showing the wiring or circuits for each subscriber's telephone apparatus.

Referring to the accompanying drawings, the numeral 1 designates the bell-box of an ordinary telephone apparatus, such as commonly used at each substation or by each subscriber on the same main line. The bell-box 1 has fitted to the door thereof the usual call-bells 2 and houses therein the ordinary generator 3, which is operated in connection with

the normally-closed circuit-closer 4 in the usual manner.

The present invention contemplates no change in the construction or manner of operating the generator and call-bells, but provides for the use of a pair of the ordinary receivers, (designated as 5 and 5^a, respectively,) which receivers when not in use are hung up on the hooks 6 of the switch-levers 7, fitted in one side of the bell-box 1.

A pair of the switch-levers 7 is necessarily employed to provide for the use of the two receivers 5 and 5^a, and each of said switch-levers is arranged to work in an opening 8, formed in one side of the bell-box and is pivotally mounted at its inner end, as at 9, on the inner extremity of a bracket-arm 10, also arranged within the opening 8 and carried by the face-plate 11, secured to the outer side of the bell-box. The inner end of each switch-lever 6 has a short pendent arm 12, to which is connected one end of a retractile spring 13, the tension of which normally serves to hold the switch-lever in an elevated position, said lever being depressed by the weight of the receiver when such receiver is hung in the hook 7 of the lever. Each of said switch-levers 6 has fitted thereto between its ends a contact-pin 14, extending beyond both sides of the lever and designed to coöperate with the switch springs or plates used in connection therewith.

In connection with each of the receiver-supporting switch-levers 6 is employed a separate set of switch springs or plates fitted to the inner side of the bell-box adjacent to the openings within which the switch-levers work, and in the diagram of Fig. 5 the separate sets or groups of switch springs or plates for each complete switch are designated, respectively, A and B, the set of switch-springs of the switch A coöperating with the switch-lever for the receiver 5, and the set of switch-springs of the switch B coöperating with the lever for the receiver 5^a. There are three pairs of contact-springs in each of the switches A and B, two pairs of which (designated, respectively, 15 15 and 16 16) are arranged side by side and are secured at their upper ends to the inner side of the bell-box above the plane of the opening 8 immediately therebelow, so that

the lower ends of the same are engaged by the contact-pin 14 of the switch-lever when in its normal elevated position. Below the two upper pairs of switch-springs 15 15 and 5 16 16 in each of the switches A and B is arranged the third pair of set-springs (designated as 17 17) and spaced apart a sufficient distance, so that the upper free ends thereof will be respectively engaged by the opposite portions 10 of the contact-pin 14 when the switch-lever carrying such pin is depressed by the weight of the receiver.

To provide for properly wiring the apparatus, there are employed three sets of binding-posts, one set of such binding-posts being conveniently arranged above the top of the bell-box and designated, respectively, 18, 19, 15 20, and 21. A second set of binding-posts is conveniently arranged below the bell-box, 20 and these posts are designated, respectively, by the numbers 22, 23, 24, and 25, while the third set of binding-posts may be conveniently fitted to the bottom of the bell-box and are respectively numbered 26, 27, 28, and 29.

25 The binding-posts 18 and 21 have connected thereto the separate terminals of the main-line wire L, said line-wire being connected up with each subscriber's apparatus in the same manner. The binding-post 18, receiving 30 one terminal of the line-wire, has a wire connection *a* with one of the contact-springs 17 of the switch A, while the binding-post 21, receiving the other terminal of the line-wire, has a wire connection *b* with one of the springs 35 17 of the switch B, so it will be obvious that when the spring 17, connected with either of the wires *a* or *b*, is not in contact with the pin of the switch-lever then one section of the line-wire leading from the subscriber's 40 apparatus will be cut out of the speaking-circuit, thereby accomplishing the result contemplated by the present invention.

The switch-spring 17 in switch A, paired with the spring having the wire connection *a*, 45 has two wire connections therewith, respectively, *c* and *d*, the latter of which wires connects with the binding-post 28, having also connected therewith one of the cords *e* of the receiver 5^a, the other cord or wire of which receiver connects with the binding-post 29. The other wire connection *c* connects with one 50 member of the circuit-closer 4, the other member of which circuit-closer has a wire connection *f* with the generator 3 and also has connected therewith one of the bell-wires *g*, the other bell-wire leading to the switch-spring 55 17 in switch B, paired with the spring having the wire connection *b*. The said switch-spring 17 in switch B, in addition to the wire connection *b*, has a wire connection *h* with the binding-post 27.

The receiver 5 has its separate cords or wires *i* respectively connected with the binding-posts 26 and 27, and said binding-post 26 has 60 a separate wire connection *j* with one of the contact-springs 16 in switch A. The other contact-spring 16 in the switch A has a wire

connection *k* with the corresponding spring 16 in the switch B, which latter spring has a circuit wire connection *l* with the binding-post 70 24 for one of the terminals of the secondary winding of the ordinary induction-coil which is used in connection with the transmitter 30. The other terminal of the secondary winding of this induction-coil has connection with the 75 binding-post 25, which binding-post has a wire connection *m* with the metallically-connected binding-posts 19 and 20, having the usual ground-wire or metallic return-circuit connection therewith. The said binding-posts 19 80 and 20 of course constitute a single connection, but are employed on the apparatus for convenience in wiring. The other spring 16 in switch B, next to the spring having the wire connections *k* and *l*, is placed in circuit 85 with the receiver 5^a through the medium of the wire connection *n*, and the springs 15 15 in both switches A and B are directly connected together by the wires *o* and *p*. In addition to the wire connections *o* and *p* the 90 springs 15 of switch B have connected therewith the battery and transmitter circuit wires *q* and *r*, leading, respectively, to the binding-posts 23 and 22, thereby completing the wire connections of the system with the local battery 95 31 and the transmitter.

When both receivers 5 and 5^a are hung upon the hooks of their respective switch-levers, the pins of these switch-levers metallically connect the lower pair of springs 17 17 in both 100 switches A and B, and thereby complete the bell-circuit, so that the subscriber can either ring up "central" or be rung up himself, as it will be seen that a complete circuit is made through the line-wire *b*, springs 17 of switch 105 B, bell-wires *g*, and bell, circuit-closer 4, wire *c*, springs 17 of switch A, wire *a*, and line. By opening the circuit-closer and manipulating the generator 3 in the usual manner central station may be rung up over that portion 110 of the line which connects with the binding-post 21 for the wire *b*.

Assuming the receiver 5 being taken down for use and the receiver 5^a left on the hook of its switch-lever, it will be obvious that the 115 portion of the main line connecting with the binding-post 18 and the wire *a* will be cut out of the speaking-circuit, thereby preventing other subscribers hearing the conversation of the subscribers whose apparatus is in use. 120 With the receiver 5 in use the springs 15 15 and 16 16 in switch A will be metallically connected by the contact-pin 14 of the spring-elevated switch-lever and the speaking-circuit will be established over one section of 125 the line—wire *b*, switch-springs 17 of switch B, wire *h*, through receiver 5, wire *j*, springs 16 of switch A, wire *k*, one of the springs 16 of switch B, wire *l*, induction-coil, and ground or return. With the receiver 5 in use the 130 transmitter and battery-circuit, including the wires *o*, *p*, *q*, and *r*, will also be closed through the springs 15 in switch A by the contact-pin of the spring-elevated switch-lever. Should

the subscriber desire to cut off communication with the portion of the main line having connection with the wire *b*, the receiver 5 is left on the hook of its switch-lever and the receiver 5^a taken down for use. With the receiver 5^a in use the speaking-circuit is completed through the switch-springs 17 of switch A and the portion of the line connected with the wire *b* is cut out of the circuit.

From the foregoing it is thought that the operation of the herein-described system of cutting out from a subscriber's telephone apparatus either terminal of the line-wire leading thereto will be readily apparent to those skilled in the art without further description, and I will have it understood that various changes may be made in the system without departing from the spirit or sacrificing any of the advantages of the invention.

Having thus described the invention, what is claimed, and desired to be secured by Letters Patent, is—

1. In a telephone system, the substation apparatus having a pair of receivers, and two separate receiver-operated switches, the main line leading to the apparatus in sections which have separate terminal connections respectively with the separate switches, circuit-wire connections including the switches and the main-line terminals in the bell-circuit, and other circuit-wire connections including the switches in circuit with the two receivers and with the transmitter, whereby the removal of either receiver for use provides for closing the speaking-circuit over one section of the main line, substantially as set forth.

2. In a telephone system, the substation apparatus having a pair of receivers and two separate receiver - operated switches, each

switch having separate upper and lower contacts, the main line having separate terminal connections, respectively with the lower contacts of the separate switches, circuit-wire connections including the lower contacts of the switches and the main-line terminals in the bell-circuit, and other circuit-wire connections between the upper contacts of each switch, and the transmitter, and the two receivers, whereby the removal of either receiver for use provides for closing the speaking-circuit over one section of the main line, substantially as described.

3. In a telephone system, the substation apparatus having a pair of receivers and two separate receiver - operated switches, each switch comprising a switch-lever normally held elevated and provided with an oppositely-extending contact - pin, two pairs of switch or contact springs arranged side by side and adapted to be simultaneously engaged by said contact-pin, and a third pair of contact-springs arranged below the other two pairs and engaged by the opposite portions of the contact-pin, circuit-wire connections for including the lower pair of springs in each switch in the main-line and bell circuits, and circuit-wire connections between the upper pairs of springs in each switch, and the local battery, the transmitter, and the two receivers, substantially as described.

In testimony that I claim the foregoing as my own I have hereto affixed my signature in the presence of two witnesses.

WILLIAM W. BENNETT.
